UNITED STATES PATENT OFFICE

DAVID W. OVAITT, OF FLINT, MICHIGAN

TELEPHONE STAND

Application filed February 21, 1923. Serial No. 620,519.

The invention relates to telephone stands and has for one of its objects the provision of a stand for detachably supporting a telephone and for adjustably supporting a telephone directory. Another object is the provision of a stand having at its opposite sides a support for a writing pad and a support for the telephone receiver, the latter support also constituting an elbow rest. A further object is the provision of a binder carrying the telephone directory and adapted to be swung outwardly from a normal position to the rear of the support flat against the wall to a position in advance thereof where the telephone directory may be readily examined.

With these and other objects in view, the invention resides in the novel features of construction and combinations and arrangements of parts as more fully hereinafter set forth.

In the drawings:

Figure 1 is a plan view of a telephone stand embodying my invention;

Figure 2 is a front elevation thereof;

Figure 3 is a side elevation thereof;

Figure 4 is a plan view of the telephone support bracket;

Figure 5 is a section therethrough;

Figure 6 is a cross section on the line 6—6 of Figure 2.

Figure 7 is a bottom detail view showing the L-shaped slot with the book supporting arm in both dotted and full line positions.

1 is the support for the telephone having the platform 1' and the upwardly extending peripheral side flanges 2 and 3 which extend rearwardly and terminate a sufficient distance from each other to permit of the telephone cord being inserted therebetween into the aperture 4 formed in the platform. The rear portions of the side flanges are apertured for the passage of suitable securing means such as screws for fastening the telephone stand to a side wall. The side flanges have the upwardly and inwardly extending ears 5 and 6 respectively at their upper edges for engaging over the base of the telephone to prevent its removal in an upward direction and also have the front end portions 7 and 8 respectively having upper edges inclined for-wardly and downwardly from their junctions with the ears to the platform. The distance between the junctions of the ears and front end portions is sufficient to allow the telephone to be readily removed by tilting the forward edge of its base upwardly to pass the base through the space, the median line of which connects the junctions, but the distance between the forward ends of the front end portions is less than the diameter of the base so that the latter cannot be laterally removed from the platform. The ears 5 and 6 have secured to their under sides suitable pads 5' and 6' respectively, preferably of felt, for protecting the finish of the telephone base.

9 is an electric light bulb mounted in the socket 10 carried by the bent pipe 11. This pipe is detachably secured against the shoulder 12' formed upon the laterally extending lug 12 at one side of the telephone support by means of the clamp 13 having transversely extending lower ears 13' adapted to engage the lower side of the pipe. This clamp is detachably secured in clamping position by the upwardly and outwardly extending thumb screw 14 threaded in the lug 12 and passing through the clamp 13. By loosening the thumb screw the electric light bulb may be swung downwardly for replacement if desired, the pipe being held from falling out by the lower ears upon the clamp. The support has the depending peripheral flange 15 which terminates sufficiently below the platform to conceal the electric light bulb and its associated socket and pipe and this peripheral flange has at the rear of the lug 12 a suitable upwardly extending notch permitting of insertion of the pipe in the lug in an upward direction. With this arrangement the bulb, socket, and pipe as well as the electric cord may be assembled to form a lighting unit which may be then assembled in the telephone support.

The telephone support has the bracket 16 which is secured to the centrally located transverse lug 17 depending from the platform 1'. This bracket extends downwardly and rearwardly to a point in substantially vertical alignment with the rear face of the securing portions of the side flanges 2 and 3 and has

at its lower rear edge a securing portion apertured to receive suitable securing means such as a screw for fastening the bracket to a side wall. 18 is a binder for the telephone directory adjustably carried upon the telephone support, this binder having the arm 19 with a spherical head 20 at its upper end which engages in a spherical socket upon the bracket 16. This socket is formed by means of the base plate 21 and cover plate 22 having complementary semi-spherical recesses. The base plate is fixedly secured to the cover plate by suitable means such as screws and the cover plate in turn is fixedly secured to the 10 top of the bracket by suitable means such as screws, the base plate having provision for the passage therethrough of the arm 19 and also having provision for the swinging of this arm. The bracket is hollow and has in its bottom the L-shaped slot 23 through which the arm 19 extends, this slot having a forwardly extending end and a laterally extending end, and being so located that the binder arm normally occupies a position in the laterally extending end and the binder is below the support and extends parallel to the side wall. However, to move the binder to a position where the telephone directory may be readily inspected, the directory is swung laterally and in the present instance to the right from its rear position flat against the wall, and then forwardly away from the wall to a position in advance of the telephone stand and rotated in a clockwise direction through 25 an angle of 90° to extend at right angles to the side wall. The binder is held in this adjusted position by means of the spring-pressed dog 24 pivoted upon the arm 19 and engageable in the notch 25 formed in the lower face of the bottom of the bracket. When it is desired to return the directory to a position below the telephone support, the dog is disengaged from its notch and the binder arm is allowed to swing rearwardly 30 and then laterally.

The binder 18 comprises the two side plates 26 hingedly connected to the curved back plate 27, the side plates having reinforcing beads 28 extending from their hinge edges. 35 These beads present the shoulders 29 which are adapted to engage the back plate upon swinging the side plates to open position to hold the side plates when opened in substantial alignment with their upper and lower edges horizontal. 30 and 31 are blocks respectively at the upper and lower edges of the back plate 27 and having the projections 32 and 33 respectively extending inwardly and suitably fixedly secured to the back plate, these projections having a curvature conforming to that of the back plate. The telephone directory when in place in the binder has its back extending adjacent to the projections and is supported upon the ledge 31 of the lower block. 34 and 35 are inwardly ex-

tending aligned pins upon the blocks 30 and 31 respectively for retaining the telephone directory in place, the pin 35 permanently engaging the block 31 and the pin 34 slidably engaging the block 30 so that it may be moved out of engagement with the telephone directory to permit of removing the same and inserting another. These pins are sufficiently spaced from the projections of their respective blocks to permit of inserting the telephone directory into the binder so that its back will occupy the spaces formed between the pins and projections. The binder arm 19 is rigidly secured in the upper block 30.

36 is a support for the telephone receiver located at one side of the telephone support 1 and fixedly secured thereto as by means of the screws 37 threadedly engaging the lug 12 of the telephone support. The receiver support has the circular recess 38 in its upper face for receiving the open end of the receiver. This receiver support may also be used as an elbow rest.

39 is a support for a writing pad fixedly secured to the telephone support 1 at the side opposite to that occupied by the receiver support by means of the screws 40. This pad support has the laterally extending lower flange 41 through which the securing screws extend, the side edge of the pad support above the lower flange being formed with a concavity 42 for closely fitting the periphery of the telephone support. 43 is a clamp at the upper end of the pad support for securing the writing pad to its support. The pad support carries the extension shelf 44 which is longitudinally slidable in the pad support below its top and has the screw 45 at its forward end engageable with the depending lug 46 upon the pad support for limiting the outward movement of the extension shelf.

For facilitating the return of the telephone cord to normal position when the telephone is being replaced upon its support, I have provided the split weight 47 adapted to embrace the telephone cord, this weight having segments 48 to which the flat resilient member 49 is secured. This resilient member is split to permit the spreading apart of the segments a sufficient distance to pass over the telephone cord, after which the segments are clamped upon the cord. This split weight is secured to the telephone cord at a point such that upon removal of the telephone from its support and pulling upwardly of the telephone cord through the opening 4 of the support platform, the split weight will not interfere with the upward movement of the telephone cord, but will always remain below the platform.

What I claim as my invention is:

1. A book support comprising a relatively stationary supporting member, a book supporting arm, means pivotally connecting the arm with said member, said means prevent-

ing movement of the arm in a direction along its length, said member being provided with an arm guide slot slidably engageable with said arm, said slot being constructed to positively guide the arm during a swinging movement thereof, first in one direction and then in a second direction substantially at right angles with that aforesaid to permit movement of the book from a position of non-use to a position convenient for use, the book in the latter position lying substantially at right angles with its first said position of non-use.

2. A book support comprising a relatively stationary supporting member, a book supporting arm, means pivotally connecting the arm with said member, said means preventing movement of the arm in a direction along its length, said member being provided with an arm guide substantially L-shaped slot slidably engageable with said arm, said slot being constructed to positively guide the arm during a swinging movement thereof, first in one direction and then in a second direction substantially at right angles with that aforesaid to permit movement of the book from a position of non-use to a position convenient for use, the book in the latter position lying substantially at right angles with its first said position of non-use.

3. A book support comprising a relatively stationary supporting member, a book supporting arm extending downwardly from said member, a ball and socket joint connecting the arm at the upper end thereof with said member, said member being provided with a substantially L-shaped slot engageable with the portion of the arm intermediate its said ends during swinging of the arm from the said ball and socket connection to guide the arm to permit movement of the book from a position of non-use to a relatively raised position convenient for use, the book in the latter position lying in a plane substantially at right angles with the plane of said first position of non-use.

4. A book support comprising a relatively stationary supporting member, a book supporting arm extending downwardly from said member, a ball and socket joint connecting the arm at the upper end thereof with said member, said member being provided with a substantially L-shaped slot engageable with the portion of the arm intermediate its said ends during swinging of the arm from the said ball and socket connection to guide the arm to permit movement of the book from a position of non-use to a relatively raised position convenient for use, the book in the latter position lying in a plane substantially at right angles with the plane of said first position of non-use, and means for retaining the book in its raised position including a dog upon said arm engageable with the forward portions of said L-shaped slot.

5. In a device of the character described,

the combination with a telephone receiving platform, a brace for said platform, said brace having a slot therein, a binder for a telephone directory or the like, an arm secured to said binder and swivelled to said brace so as to be movable in said slot successively in two directions substantially at right angles to position the directory rearwardly or forwardly to a position convenient for using the directory.

6. In a device of the character described, a supporting member, a binder for a telephone directory or the like, a movable arm swivelled at one end to the supporting member and having its opposite end secured to said binder, said member having means engageable with an intermediate portion of said arm for controlling the direction in which said arm may be moved for positioning the directory selectively from a rearward position to a forward position convenient for use.

7. In a device of the character described, a supporting member adapted to be secured to a wall or the like, a binder for a telephone directory, a movable arm secured at opposite ends to the binder and member respectively, said member being provided with a slot engageable with an intermediate portion of said arm for guiding the arm to move the directory from a position flat against the wall forwardly to a position convenient for use.

8. A book support comprising a supporting member provided with a slot of angular formation, and a book supporting arm pivotally connected to said member and movable in and guided by said slot for carrying the book from a position of non-use to a position convenient for use.

9. A book support comprising a supporting member provided with an L-shaped slot, and a book supporting arm pivotally supported upon said member and movable in and guided by said slot for carrying the book from a position of non-use to a position convenient for use.

10. A book support comprising a supporting member provided with a slot of angular formation, a book supporting arm movable in and guided by said slot for carrying the book from a position of non-use to a position convenient for use, and a ball and socket joint connecting the arm to said supporting member for permitting the aforesaid movement of said arm in the slot.

In testimony whereof I affix my signature.
D. W. OVAITT.
